(57) **CLAIM**

The ornamental design for a solar powered outdoor light, as shown and described.

DESCRIPTION

FIG. 1 is a perspective view of a solar powered outdoor light embodying the new design.

FIG. 2 is a left side elevational view of the design depicted in FIG. 1.

FIG. 3 is a right side elevational view of the design depicted in FIG. 1.

FIG. 4 is a front elevational view of the design depicted in FIG. 1.

FIG. 5 is a rear elevational view of the design depicted in FIG. 1.

FIG. 6 is a top plan view of the design depicted in FIG. 1; and,

FIG. 7 is a bottom plan view of the design depicted in FIG. 1.

The dotted lines are for illustrative purposes only and form no part of the claimed design.
